UNITED STATES PATENT OFFICE.

HENRY ROBERT EASON, OF LONDON, ENGLAND.

PHOTOGRAPHIC-PRINTING APPARATUS.

Application filed December 28, 1921. Serial No. 525,458.

To all whom it may concern:

Be it known that I, HENRY ROBERT EASON, subject of the King of the United Kingdom of Great Britain and Ireland, and resident 5 of London, England, have invented a certain new and useful Improvement in Photographic-Printing Apparatus, for which I have filed an application in Great Britain, 26,723, September 18, 1920.

10 This invention relates to photographic printing apparatus and has for its object to provide an improved construction and arrangement of such apparatus adapted for use inter alia in producing multiple designs, 15 images or impressions on plates, lithographic stones or the like, for the purpose of printing in one or more colours therefrom by any of the usual processes.

In accordance with one feature of the 20 invention the improved apparatus includes a framework or carriage which can be traversed over a bench or table on which are arranged the sensitized surface and the negatives or the like, the framework being arranged to exert pressure on the negatives during the printing operation so as to insure 25 perfect contact between the negative and the sensitized surface. In accordance with a further feature of the invention I 30 arrange on the sensitized surface supported on the bench or table a rectangular framing of wood or other suitable material with adjustable subdividing bars and with true right angles, when required, for the purpose 35 of registering the position of the images on the sensitized surface by placing the right angles of the negative or plurality of negatives or the like into the right angles of the registering frame.

40 In accordance with one embodiment the carriage adapted to travel over the bench or table supporting the sensitized surface on which the registering frame is placed supports an auxiliary carriage adapted to 45 travel transversely of the main carriage so that the auxiliary carriage may be brought into a position directly above any part of the registering frame on the bench or table. From the auxiliary carriage are suspended

50 a plurality of legs adapted to be lowered into contact with a thick covering sheet of plate glass laid on the negative or the like in the frame in such wise as to hold the negatives rigidly in position. Suitably there 55 is interposed between the freely hanging legs and the auxiliary carriage an inflatable

member on inflation of which the legs are forced by the pneumatic pressure against the covering plate glass. The auxiliary carriage preferably carries also electric or 60 other lamps for the purpose of printing by the light emitted thereby upon the sensitized plates supported as above described.

The invention is illustrated in the accompanying drawings in which Fig. 1 shows 65 in side elevation partly in section the traveling framework or carriage supported on an extension of the table. Fig. 2 is a plan view showing the main and auxiliary carriages with parts omitted for the sake of clearness. 70 Fig. 3 is a section through the supporting bench or table and showing the manner in which the main carriage is supported thereon. Figs. 4 to 7 represent in plan several 75 forms of registering frames.

As shown in the drawings and in accordance with the invention the improved apparatus includes a bench, or table *a* along two outside edges of which are arranged on bars *b* bolted to the table supporting rails *b'* 80 for rollers *c'* mounted on laterally extending bars *c* of an upright carriage *d* the bars *c* tending to prevent the raising of the carriage from the table. On the upper surface *d'* of this carriage on rails *e* is mounted an auxiliary sliding carriage *f* in such manner that this auxiliary carriage may travel transversely of the main carriage. Suspended from this auxiliary carriage by means of a screw threaded rod *h* engaging 85 in a screw threaded bush *i* attached to the carriage is a separable spring-connected housing *k* containing an inflatable elastic vessel *l*, and from the lower portion of this housing are suspended a plurality of 90 depending legs *m*. From a framing *n* attached to the auxiliary carriage *f* are suspended electric or other lamps *o* which travel with the carriage. 95

On the table top *a'* is placed on a slate or other bed *p* a registering frame *q* such as shown in Figs. 4 to 7. This frame is fitted with subdividing bars *q'* formed with true right angles into which the negative or negatives or the like from which the impression is to be made on the sensitized surface are inserted. On the top of the negative is placed a covering plate glass not shown.

In using the apparatus the negative or the like is inserted in its compartment in the 110 registering frame and fixed therein as by a strip of wood, the covering plate glass is laid

thereon and the other spaces not being utilized in the frame are suitably covered to protect the sensitized surface beneath the frame. The carriages are now traversed 5 until the depending legs are in position above the covering glass plate. By means of the wheel r the screw threaded rod is turned until the legs bear on the covering glass plate whereupon air is forced through 10 the pipes to the inflatable vessel whereupon the depending legs are caused to press more firmly on the covering plate glass. The electric or other lamps are switched on and the printing carried out. When the printing 15 operation is completed air is allowed to escape from the inflatable vessel, the wheel r is turned until the legs are clear of the covering glass plate and the carriages moved along the table out of the way to permit 20 access to the surfaces treated.

I claim:—

1. Photographic printing apparatus including a table to receive a sensitized surface and photographic plate, a carriage having guided movement upon said table into position over said plate, and pressure-applying means mounted on said carriage and supported thereby for exerting pressure on said plate, substantially as and for the purpose set forth.

2. Photographic printing apparatus including a table for a sensitized surface and a photographic plate, a carriage adapted to be moved along said table into position over 35 said plate, and pressure-applying means mounted on said carriage for exerting pressure on said plate, said pressure-applying means including an auxiliary carriage supported on said first-mentioned carriage, depending legs supported by such auxiliary carriage and means for lowering said depending legs to exert pressure on said plate.

3. Photographic printing apparatus including a table to receive a sensitized surface and a photographic plate, a carriage adapted to be moved along said table into position over the plate, and pressure-applying means mounted on said carriage for exerting pressure on the said plate, said pressure-applying means including an auxiliary carriage supported on said first-mentioned carriage, depending legs supported by such auxiliary carriage and an inflatable elastic chamber interposed between the depending legs and said auxiliary carriage, substantially as and for the purpose set forth.

4. Photographic printing apparatus in-

cluding a table to receive a sensitized surface and a plurality of photographic plates, a carriage adapted to be moved along said table into position over any of said plates, and pressure applying means mounted on said carriage for exerting pressure on any of said plates, substantially as and for the purpose set forth.

5. Photographic printing apparatus including a table for a sensitized surface and a plurality of photographic plates, a carriage adapted to be moved along said table into position over any of said plates, and pressure-applying means including an auxiliary carriage supported on said first-mentioned carriage, depending legs supported by such auxiliary carriage and means for lowering said depending legs to exert pressure on any of said plates.

6. Photographic printing apparatus including a table to receive a sensitized surface and a plurality of photographic plates, a carriage adapted to be moved along said table into position over any of said plates, and pressure-applying means mounted on said carriage for exerting pressure on any of said plates, said pressure-applying means including an auxiliary carriage supported on said first-mentioned carriage, depending legs supported by such auxiliary carriage and an inflatable elastic chamber interposed between the depending legs and said auxiliary carriage, substantially as and for the purpose set forth.

7. Photographic printing apparatus including a table adapted to receive a sensitized surface and a photographic plate thereon, a carriage having guided movement on the table thereby to be positioned above the plate, pressure applying means for exerting pressure on the plate supported by the carriage and movable therewith, manually controlled means between the carriage and the pressure applying means for moving the same toward and from the table, and fluid pressure control means between said last named means and the pressure applying means for operating said means to clamp the plate upon the table.

In testimony whereof I have signed my name to this specification in the presence of two subscribing witnesses.

HENRY ROBERT EASON
